UNITED STATES PATENT OFFICE

SCHUYLER C. KNAUR, OF DENISON, TEXAS

EXPANDING BIT

Application filed June 29, 1929. Serial No. 374,808.

My invention relates to drills for use in deep well drilling for oil, gas, water, sulphur and the like.

In deep well drilling a large item of expense is incurred in withdrawing the drill from the hole to sharpen or replace the cutters. Where the hole is deep it sometimes happens that a third of the time is thus consumed. This is not only expensive in the extra amount necessary to pay the drilling crew, but also in the time wasted where production should be obtained.

It is an object of my invention to provide a drill that may be withdrawn for sharpening or replacement in a minimum of time without the necessity of removing the drill stem.

I contemplate the removal of the drill by means of a cable which may be reeled up quickly. The drill to which the cable may be engaged is adapted to collapse within the drill stem so that it may be readily removed.

It is a further object to provide a reaming bit, to be employed with a pilot bit, the cutters of the reamer being easily and positively expanded, and of simple construction so that the device is cheap and economical to manufacture and not liable to get out of order or fail to function positively at all times. I desire to eliminate springs or levers or similar elements which might get clogged or jammed and thus fail in use.

In the drawings herewith Fig. 1 is a central longitudinal section through a device embodying my invention, the expanding elements being in cutting position at the lower end of the drill stem.

Fig. 2 is a broken detail illustrating the cutting blades in contracted position where they may be withdrawn through the drill stem to the surface.

Fig. 3 is a broken detail in elevation illustrating the manner in which the blades are supported during rotation.

In constructing my device I connect at the lower end of a drill stem 1 a shoe 2, which is of slightly heavier construction than the drill stem and is formed to cooperate with my expanding bit. The inner diameter of the shoe is decreased slightly over that of

the drill stem to form a shoulder 3, upon which a drill nipple 4 may be supported. The lower end of the shoe is formed with two approximately opposite downwardly extending arms 5. As seen in Fig. 3, these arms may be beveled forwardly at 6 although this is not a necessary feature.

The drill which I employ may be a fish tail bit or any common type of drill which may be preferred. I have shown a fish tail bit as having the usual threaded connection with the lower end of the drill nipple 4, previously referred to. Said drill nipple is of tubular construction. It has a peripheral flange 8 spaced slightly from the upper end, said flange being adapted to engage upon the shoulder 3 in the shoe and is supported by gravity thereon.

Spaced slightly above the pilot bit 7, I provide a plurality of expanding cutter blades 9. Said blades are approximately triangular in shape and are pivotally supported upon pins 10 extending through the upper ends of said blades and through the walls of the slots 11 in the nipple, in which said blades are mounted. The slots 11 in the nipple, which accommodate the blades, are of sufficient width to allow free movement of the blades therein, the slots being approximately opposite but slightly offset so that when the blades are moved inwardly to contracted position, as shown in Fig. 2, they may pass each other and overlap to some extent. It is to be noted that the inner sides of the blades, indicated at 12, are straight so that they may contact with an inner mandrel 13.

The mandrel 13 is adapted to project above the nipple 4 and may be provided with a head 14 of any preferred construction, whereby it may be engaged by a setting tool or similar device so that it may be lowered into the well and released and again engaged for withdrawal. Setting tools adapted for this purpose are of ordinary and common construction and need not be shown. The mandrel is of suitable outer diameter to fit slidably within the nipple 4. The lower end of the mandrel is flattened slightly on each side at 15 to abut against the inner sides 12 of the blades so as

to provide a rigid and firm support for the blades when said blades are projected.

The connection between the mandrel 13 and the nipple 4 is provided by means of a transverse pin 16, which is supported within the walls of the nipple 4 and extends diametrically through slots 17 formed in the opposite sides of the mandrel. Each slot 17 is accurately positioned relative to the blades 9 so as to allow sufficient longitudinal play or sliding movement of the mandrel relative to the nipple so that when the mandrel is drawn upwardly, so as to bring the lower end of the slot 17 in contact with the pin, as shown in Fig. 2, the lower end of the mandrel will be entirely free of the cutters so that they may be moved inwardly into retracted position, the length of the slot being sufficient, however, so that when the mandrel is lowered between the cutters, as shown in Fig. 1, the pin 16 will be toward the upper limit of the slot.

It is to be noted also that when the nipple 4 is in position with the flange 8 resting upon the shoulder 3 in the shoe, the slots 11 in which the blades are mounted, will be sufficiently beyond the lower end of the shoe so as to allow the blades to be projected outwardly. When said blades are thus projected, as into the position shown in Fig. 1, the outer edges of the blades will come into contact with the lower beveled shoulders 18 upon the shoe, thus limiting the outward movement of the blades and clamping said blades rigidly between the lower end of the mandrel and the inner wall of the shoe. Also, when the drill stem is rotated in the usual right-hand direction, the arms 5 upon the shoe will engage against the rearward sides of the blades and exert a driving action thereon and support them from the rear.

The operation of my device will now be understood. The drill stem may be introduced into the hole and may remain there throughout the drilling of the well. The bit, including the pilot drill 7 and the expanding blades 8, may be lowered into the well to cutting position. While the device is being thus lowered the nipple and the bits will be supported from the mandrel and the weight of the nipple will move the pin 16 in the said nipple to the lower end of the slot 17 in the mandrel and the blades will be contracted below the mandrel, as seen in Fig. 2. When the bottom of the well has been reached the bit will rest upon the bottom of the hole and the weight of the mandrel will move said mandrel downwardly relative to the nipple, contacting with the inner edges of the blades and forcing said blades outwardly to the position shown in Fig. 1. The flattened sides of the mandrel will engage between the blades and form a rigid and firm support for said blades on their inner sides and the outer edges of the blades will be clamped against the shoe. When the

blades are thus expanded it will be seen that a downward pressure upon the drill stem will be exerted against the blades and a driving torque will be exerted against the rearward sides of the blades to move them with the drill stem to cut the wall of the hole. The pilot drill 7 will cut a hole of a size to allow the nipple to move downwardly but the blades 9 will enlarge this hole to allow the free downward descent of the drill stem. When the blades become dulled and need repair or replacement a fishing tool may be lowered into the well to engage the head 14 upon the mandrel, and when said mandrel is drawn upwardly the blades will move into retracted position so that the device may be withdrawn from the well.

The advantages of this construction lie in its simplicity. There are no springs or levers or other similar parts which may be clogged or broken or interfere with the positive action of the cutting blades. The blades are projected into cutting position in a positive manner and when the device is to be withdrawn there is nothing to interfere with the ready retraction of the blades so that the cutters may be withdrawn to the surface for repair. The further advantages will be obvious to those skilled in the art.

What I claim as new is:

A well drill including a drill stem, a shoe thereon, a drill nipple slidable within said shoe, a pilot drill at the forward end of said nipple, cutting blades in said nipple above said drill, said blades being pivoted to be swung outwardly from a normally retracted position in said nipple to cut a hole of larger diameter than said pilot drill, and a mandrel in said nipple adapted to fit between said blades and move them into cutting position, said blades having straight inner sides adapted to abut against the said mandrel for their entire length and be thus held rigidly in expanded position, and downwardly projecting legs on said shoe to support said blades from their rearward sides during rotation of said drill and communicate rotation to said pilot drill.

In testimony whereof I hereunto affix my signature this 22d day of June, A. D. 1929.
